ATTORNEYS:

DEVICE FOR REPLACING FUZE PARTS

Andrew J. Grandy, North Hills, Pa., assignor to the United States of America as represented by the Secretary of the Army

Filed Feb. 25, 1959, Ser. No. 795,568

4 Claims. (Cl. 73—167)

(Granted under Title 35, U.S. Code (1952), sec. 266)

The invention described herein may be manufactured and used by or for the Government for governmental purposes without the payment to me of any royalty thereon.

This invention relates to the inspection or repair of fuzes including a bore-riding safety pin which is released by the set-back force incident to the firing of a projectile and functions to arm the fuze after the projectile has travelled a predetermined distance. The principal object of the invention is to provide a device whereby the bore-safety pin may be removed from the fuze more safely and with less effect than has been possible in the past.

In the field maintenance of such fuzes, it is sometimes desirable to inspect the bore safety pin or to replace it by another adapted to provide a different time delay between the firing of the projectile and the arming of the fuze. Heretofore this operation has involved removal of the fuze from the projectile, removal of the booster, unstaking and removal of a slider, unstaking and removal of a slider detent, and unstaking and removal of a bore safety pin detent. The device of the present invention eliminates most or all of these steps by (1) depressing the firing pin to lock parts otherwise released by a removal of the bore-safety pin and (2) energizing an electromagnet whereby the set-back pin is disengaged from the bore-safety pin.

The invention will be better understood from the following description when considered in connection with the accompanying drawings and its scope is indicated by the appended claims.

Referring to the drawings:

Fig. 1 illustrates the invention as applied to a fuze which has been removed from the projectile, and

Fig. 2 shows it as applied to a fuze which is fixed to a projectile.

The fuze is a conventional type which includes a bore-safety pin 10, a set-back pin 11 which is biased into a slot in the pin 10 by a spring 12, and a slider 13 which rides in an aperture 14 and is backed in its illustrated position by the pin 10. The slider 13 bears a primer (not shown) and is spring biased so that it moves this primer into alignment with a firing pin 15 and an aperture 16 when the bore-safety pin is drawn out of engagement with it. The firing pin 15 is held away from the slider 13 by a spring 17 which is compressed to bring the firing pin into contact with the primer upon impact of the projectile against the target. The aperture 16 leads from the primer to the booster charge by which the main charge of the projectile is ignited.

The device for removing the bore-safety pin 10 and from the fuze includes an electro-magnet which has a winding 18 and a core 19 with its upper surface arranged to seat the fuze. Through input leads 20, a switch formed by fixed contacts 21 and a movable contact 22, current is supplied to the coil 18 when the switch 21—22 is closed.

Operation of this switch is effected by an L-shaped control member 23 which rides in a slot in an extension 24 fixed to the core 19. The arm 23 has a projection 25

which engages the head of the pin 10 when it is aligned therewith.

With the various parts in the positions illustrated by Fig. 1, the slider 13 is locked in position by engagement with the firing pin 15, the set-back pin 11 is withdrawn from the bore-safety pin 10 by electro-magnetic action and a slight rotation of the fuze disengages the head of the pin 10 from the projection 25 so that it may be forced out by a spring 26.

Under these conditions, the pin 10 may be inspected and reinserted. Also it may be replaced by a new pin or a pin providing a different time delay between the firing and arming of the projectile. In any case, a slight rotation of the fuze brings the pin's head into engagement with the projection so that it is properly positioned in the fuze.

Raising the arm 23 successively deenergizes the electromagnet 18—19 and releases the pressure on the nose of the fuze. Deenergization of the electromagnet allows the set-back pin 11 to interlock with the bore-safety pin 10. Release of the pressure on the nose of the fuze allows the spring 17 to detach the firing pin 15 from the slider 13. This puts the fuze into operative condition.

Fig. 2 illustrates a form of the invention which is adapted for use with a fuze fixed to a projectile. In this case, an annular electromagnet 26 is supported on an annular base 27, the opening through the electromagnet and base being of a size to receive a projectile body 28. The operation of this modification of the invention is the same as that previously described.

I claim:

1. In combination with a fuze having a bore-safety pin which is locked in place by a set-back pin and is interlocked with a slider arranged to move a primer into alignment with a firing pin and wherein a nose in the fuze is adapted to cooperate in attaching and detaching the firing pin from the slider, the combination therewith of a device attachable to said fuze during an inspection of said bore safety pin and removable therefrom subsequent to said inspection comprising an electromagnet disposed axially rearwardly adjacent of said fuze, an arm extending outwardly from said electromagnet and integral therewith, a current supply in circuit with said electromagnet, an L-shaped control lever exteriorly of said fuze and articulating between said nose and said arm, a pair of spaced electrical contacts fixed on said arm and interrupting said circuit, an electric contact extending from said lever for engaging said fixed contacts to close said circuit and energize the electromagnet when the lever is in a depressed position, said depressed lever generally simultaneously urging the nose inwardly of said fuze for detaching the firing pin from the slider.

2. A device as described in claim 1 further characterized by said arm having a slot therein for guiding the movement of said control lever.

3. The device of claim 1 further characterized by an abutment on said lever for engaging a bore safety pin head to prevent the ejection of the bore-safety pin from said fuze.

4. In combination with a fuze separated from its projectile, said fuze having a bore-safety pin which is locked in said fuze by a set-back pin and is interlocked with a slider arranged to move a primer into alignment with a firing pin and wherein a nose in the fuze is adapted to cooperate in attaching and detaching the firing pin from the slider, the combination therewith of a device attachable to said fuze during an inspection of said bore safety pin and removable therefrom subsequent to said inspection comprising an electromagnet having a core with a winding therearound, said core providing a surface at an upper end for seating the fuze thereon, an arm extending outwardly from said core and integral therewith, a current

70

supply in circuit with said electromagnet, an L-shaped control lever exteriorly of said fuze and articulating between said nose and said arm, a pair of spaced electrical contacts fixed on said arm and interrupting said circuit, an electric contact extending from said lever for engaging said fixed contacts to close said circuit and energize the electromagnet when the lever is in a depressed position, said depressed lever simultaneously urging the nose inwardly of said fuze for detaching the firing pin from the slider.
